UNITED STATES PATENT OFFICE.

ISAAC A. ULLMANN, OF BROOKLYN, NEW YORK.

DEVICE FOR ATTACHING COLLARS TO SHIRTS.

1,115,258.

Specification of Letters Patent. Patented Oct. 27, 1914.

Application filed January 16, 1912. Serial No. 671,452.

To all whom it may concern:

Be it known that I, ISAAC A. ULLMANN, a citizen of the United States, and a resident of Brooklyn, county of Kings, and State of New York, have invented certain new and useful Improvements in Devices for Attaching Collars to Shirts, of which the following is a specification.

My invention relates primarily to devices for attaching collars to shirts, the object being to dispense with the ordinary collar button, and with its shank, head and base, which, when in use, press against the neck of the wearer.

In my invention I use the ordinary shirt and ordinary collar, and achieve the desired result without any increase of expense, and in fact, my improved collar attaching device is much cheaper to manufacture than the ordinary collar button.

In the drawings forming part of this specification Figure 1 represents my improved device placed in operative position in a neckband of a shirt; Fig. 2 represents an enlarged view of my invention; Fig. 3 is a side view thereof.

Referring to the drawings, like letters refer to like parts.

A is the rear view of a shirt showing the neckband B with a pocket in the neckband formed by the stitches D and the stitching across the top of the neckband. This pocket is open at the bottom in the ordinary way so as to permit the insertion of collar retaining means, and the pocket is provided with a button hole C, all of which is in shirts as generally constructed at the present time.

My collar retainer consists as shown in Fig. 2 of the flat body member E, the flat head G and the flat connecting member F, all in the same plane. The member F at its point of connection with the head G is narrower than at its point of connection with the body E, and ordinarily I prefer to make the connecting member F at the point where it connects with the body member E substantially the same width as the head G, which I prefer to make substantially as wide as the collar button hole in the pocket of the shirt is long. The lower edge of the body member E extends laterally in each direction to provide shoulders on which the device may be turned in the process of insertion. In the preferred form, I make the head G so that it will have two portions H projecting rear-

wardly in the direction of the member E to a point beyond the point where the head connects with the connecting member F, the object of the head being to retain the collar in place while it is being adjusted at some other point of connection.

In operation, my improved device is placed into the pocket of the neckband with the head G projecting outward through the button hole in an upward direction when it is drawn through the button hole until substantially the entire retainer with the exception of the body member E projects upward through the button hole then the head is turned downward, as shown in Fig. 1, the bottom edge of the body portion forming shoulders which abut the outer fold of the shirt band and about which the device is turned, and the body assumes a position as shown by dotted lines in Fig. 1. It will be readily seen that in this position the retainer is substantially locked within the pocket. When the collar is in position, the head G and the connecting member F extending through the button hole in the rear of the collar, the pressure of the collar on the neckband above the button hole and below the button hole will lock the device in position. The head G and the projecting member F may, if desired, be used to hold the necktie down in the rear of the collar when a standing collar is used, or whenever any collar is used in which said use is advisable.

My improved collar retainer I preferably make of a substantially rigid metal, although, if desired, it could be made of a metal which was slightly flexible, or could be made of bone or ivory, or any other suitable material, but it is necessary that the material used be sufficiently rigid so that the upward pull of the collar would not bend the connecting member F upward, for if this occurred, the material would permit the collar to disengage itself from the retainer when the projecting member had bent over on the neckband so as to assume a position above the collar button hole rather than below it. It is essential that in use this projecting member F always project so that the head points downward in relation to the collar button hole.

Having thus fully described my invention, what I claim as new and desire to secure by Letters Patent, is:

A device adapted to be inserted in the rear

collar button-hole of a two fold shirt band, comprising a laterally extending relatively narrow body portion, a flat collar attaching tongue projecting downwardly from the lower edge of the body portion, and a laterally enlarged head joined to the lower end of said tongue to prevent the button becoming accidentally disengaged from the button-hole, the lower edge of the body portion 10 extending laterally in both directions from the base of the tongue to provide shoulders on which the device may be turned in the shirt band pocket in the process of insertion, and the upper edge of said body portion being 15 perpendicular to the longitudinal axis

of the button so as to present an elongated supporting edge, which is adapted to lie adjacent the fold in the shirt band, whereby tilting of the button in the button-hole is prevented, and said body portion, tongue 20 and head all forming a substantially flat button.

In testimony whereof, I have signed my name to this specification, in the presence of two subscribing witnesses.

ISAAC A. ULLMANN.
